APPARATUS FOR FLAME HARDENING

Richard J. Wolf, Chicago, Ill.

Application July 12, 1941, Serial No. 402,220

6 Claims. (Cl. 266—4)

This invention relates to improvements in apparatus for flame hardening, and more particularly to apparatus for the flame hardening of bevel gears and the like.

In the process of flame hardening, it is desired to raise the temperature of a localized surface area of the articles to be hardened above the critical temperature of the steel thereof, and then quench the heated area by means of a suitable medium to impart the desired surface hardness to the metal. In such a process, the depth of hardness is controlled by the degree of heat penetration at critical temperature and the severity of the quench.

It is an object of my invention to provide an apparatus of the character stated by which the heating and quenching may be applied in such a manner as to prevent the latter from interfering with the application of the heat to the gears.

My invention contemplates effecting a relative movement of the flame and quenching means in accordance with the contour of the gear teeth, thereby enabling the uniform treatment of bevel gears and the like, and employs a multiplicity of torches or other heat sources, thereby enabling increased production in a flame hardening treatment while at the same time maintaining controlled uniformity of the treatment.

Further objects are to provide an apparatus for the purposes stated including indexing means for alignment of the torches and gears, to provide a simple and efficient mounting for the multiplicity of torches or flame devices, and to mount said torches or flame devices and their service equipment in efficient and convenient relation to a tank or container for the quenching medium.

Additional objects and advantages will become apparent from the following description taken in connection with the accompanying drawing wherein:

Fig. 1 is a top plan view of a flame hardening apparatus embodying my invention; and

Fig. 2 is a vertical sectional view thereof, taken on the line II—II of Fig. 1.

Referring to the drawing, 2 designates a cylindrical tank or container having a pedestal or support 4 mounted centrally within the tank, said pedestal having its upper end provided with a rotatable work-receiving table or chuck 6, said chuck being provided with a series of vertically extending radially expandable jaws 8 for receiv-

ing and supporting a bevel gear 9 by the central bore or aperture of the latter.

A pair of circular tracks 13 are concentrically disposed about the tank 2, being supported from the latter by a series of brackets 14. Movable on the tracks 13, I provide a plurality of carriages 15 mounting and supporting torches or heating devices 16. A pair of torches may be provided on each carriage 15, said torches being radially positioned with respect to the common vertical axis of gears 9 and being slidably adjustable toward and away from the gears as by means of supporting rods 17 freely reciprocable in pivoted tubular supports 18 of the carriages. Also, the torches 16 are preferably pivoted at 19 at their point of connection with their respective rods 17, thereby permitting pivotal movement for alignment of the torch tips 20 with the gear teeth 11.

Hence, each of the pairs of torches 16 may be properly spaced for impingement of the flames of tips 20 thereof on opposite sides of selected gear teeth 11 of the bevel gear 9, and said pairs of torches may be moved on their circular tracks 13 upon supporting carriage wheels 21 to selectively position said pairs of torches in relation to the teeth of the gear. Torch tips 20 are preferably disposed at an angle to the body of the torch so as to permit the positioning thereof in substantial alignment with the angular slope of the gear teeth, as particularly shown in Fig. 2.

In the event that the gear 9 has an even number of teeth, the carriages 15 may be diametrically disposed on opposite sides of the tank 2, by means of locking pins 22 engageable in diametrically disposed recesses 23 in the rim or body of the tank. Also, when treating a gear having an even number of teeth, upon diametrically locating the carriages and torches in the manner described, the chuck 6 may be rotated as by means of a handle 24, to thereby align selected gear teeth with said torches. A retractable radial index finger or pawl 25 is adjustably secured over the upper edge of the tank 2 for entrance between the teeth of the gear 9 to thereby maintain the same against rotation and in alignment with the torches.

For the purpose of effecting relative movement between torches and gear, each pair of radially convergent torches is provided with a plunger 26 slidable in a bearing 27 centrally of the carriage 15, whereby said plunger extends centrally between the radially disposed torch supporting rods 17. The inner terminal of said plunger has a guide finger 28 pivoted thereto

for free guiding engagement with the gear teeth.

Between said finger 28 and the support 27, links 29 are pivoted to the plunger as at 30, said links outwardly diverging and having pivotal connection 31 with the outer terminals of the rods 17. Hence, upon moving the plunger 26 inwardly toward the gear 9, the links 29 effect a corresponding radially inward movement to move the torch tips 20 along the selected gear teeth. Weights 32 are connected to the outer ends of the plungers 26 by cables 33 passed over pulleys 34 on carriages 15 inwardly of said plunger ends to effect the said travel of the torches, the guide fingers 28 maintaining said moving assembly in proper relation to the gear teeth.

Each of the torches 16 is provided with a water or quenching liquid connection, as by flexible conduits 35, from arcuate mains 36 supported on the underside of the brackets 14, said mains having hose cocks 37 for said flexible conduits. The water or other liquid thus supplied to the torches is conveyed therein to the tips 20 and discharged from the latter at the lower outward portion of the inclined tips, as indicated at a. Hence, as the torch flame is emitted from the upper inner terminal of the tip, as indicated at b, the heating thereby is first applied to the gear teeth as the torches are moved radially inward as described, followed by the application of the quenching liquid thereto at a lower level or plane, thereby preventing the liquid from interfering with the progressive preheating of the gear teeth as the torches move inwardly therewith. The waste liquid will fall by gravity into the tank 2 for reuse if desired.

As the selected teeth of the gear 9 are heated and quenched, the torches are retracted, the gear is rotated and indexed by the device 25 for alignment of other teeth with the torches, and the heating and quenching operation is repeated as before. Hence, the foregoing cycle is repeated until all of the gear teeth of the gear 9 have been subjected to the hardening treatment.

When it is desired to harden a gear 9 having an uneven number of teeth, the indexing finger 25 is employed as before, and the pairs of torches adjusted for proper convergence upon opposite faces of the selected gear teeth. However, since the carriages 15 will no longer be diametrically opposed, the same are provided with track clamps 38 for securing the carriages and torches to the tracks 13 in selected adjustment about the gear.

For the purpose of supplying the torches 16, arcuate oxygen manifolds 39 and acetylene manifolds 40 are mounted on the under sides of the brackets 14, said manifolds having a plurality of spaced hose cocks 41 for connection with the torches 16 as by flexible conduits or hoses 42. The manifolds 39 and 40 as well as the arcuate mains 36 for the quenching liquid may be supplied from suitable outside sources by suitable connections, not shown.

Thus, by the apparatus of my invention, I am enabled to flame harden a bevel gear or the like, with a uniform hardening treatment throughout. My improved apparatus provides a positive and simple control for carrying out the heating and quenching operations in order to maintain the desired uniformity of heat treatment.

Various changes and modifications are contemplated within the scope of the following claims.

I claim:

1. In a flame hardening device for bevel gears and the like, a support for mounting a gear to be

treated, a pair of related combined flame and quenching devices adapted for linear movement radially of the gear adjacent the gear teeth, means mounting said devices in adjustable relation circumferentially about the gear, means common to the pair of devices for moving the same radially along the gear teeth to progressively heat and quench said teeth, and a guide member for each of said pair of devices slidable in the gear teeth.

2. In a flame hardening device for bevel gears and the like, the combination with means for supporting a bevel gear to be treated, of a series of pairs of combined flame and quenching devices, means mounting each of said pairs of devices for movement radially of the gear adjacent the teeth thereof, means for adjustably positioning said mountings circumferentially about the gear, a plunger on each of said mountings slideable radially with respect to the gear, a guide finger on each plunger slidable in the gear teeth, means for moving said plungers radially of the gear, and linkage connecting each plunger with its pair of combined flame and quenching devices for moving the latter radially along the gear teeth.

3. Apparatus for flame hardening bevel gears and the like, including a support for mounting a gear to be treated, a trackway about the support, carriages movable on said trackway, each of said carriages having a pair of combined flame and quenching devices mounted thereon for linear movement radially with respect to the gear teeth, and means common to each pair of devices for moving the same radially along the gear teeth to progressively heat and quench said teeth.

4. Apparatus for flame hardening bevel gears and the like, including a support for mounting a gear to be treated, a trackway about the support, carriages movable on said trackway, each of said carriages having a pair of combined flame and quenching devices mounted thereon for linear movement radially with respect to the gear teeth, a plunger slidably mounted on each carriage between the said devices thereon, a guide finger on each plunger slidable in the gear teeth, links pivotally connecting the pairs of devices with the plunger intermediate each pair, and means for moving said plungers radially with respect to the gear teeth to progressively heat and quench said teeth by said devices.

5. Apparatus for flame hardening bevel gears and the like, including a support for mounting a gear to be treated, indexing means removably engaging the gear teeth for securing said gear against rotation on its support, a trackway about the support, carriages movable on said trackway, each of said carriages having a pair of combined flame and quenching devices mounted thereon for linear movement radially with respect to the gear teeth, a plunger slidably mounted on each carriage between the said devices thereon, a guide finger on each plunger slidable in the gear teeth, links pivotally connecting the pairs of devices with the plunger intermediate each pair, and means for moving said plungers radially with respect to the gear teeth to progressively heat and quench said teeth by said devices.

6. Apparatus for flame hardening bevel gears and the like, including means for supporting a bevel gear with the axis of rotation thereof vertical, means for securing said gear against rotation on its support, a trackway surrounding said gear and support, carriages individually movable on said trackway, each of said carriages having

a pair of torch supporting rods mounted thereon for linear movement radially with respect to the gear teeth, combined flame torches and quenching devices adjustably mounted on the inner ends of said rods, a plunger slidably mounted on each carriage, a guide finger on each plunger slidable in the gear teeth, links pivotally connecting the

5 rods and plungers, and means for moving said plungers radially with respect to the gear teeth to progressively heat and quench said teeth by means of said combined torches and quenching devices.

RICHARD J. WOLF.
